CIGARETTE MACHINE TONGUE AND PROCESS FOR MANUFACTURE THEREOF

James W. Warren, Lynbrook, N. Y., assignor to
American Machine & Foundry Company, a corporation of New Jersey

Application May 12, 1944, Serial No. 535,270

15 Claims. (Cl. 131—66)

1

This invention relates to continuous rod cigarette machines, more particularly to the construction of and process for manufacturing the tongue which compresses into a predetermined cross-section the continuous layer of shredded tobacco which is advanced by the cigarette paper into the rod former wherein the edges of the paper are overlapped to form a cigarette rod.

In the operation of cigarette machines it has been found that due to differences in different tobacco batches or in atmospheric conditions, the tobacco layer as it is advanced under the tongue will occasionally hesitate momentarily and thereby create soft spots in the cigarette rod. This condition is called a "choke," and although it may be avoided by adjusting the tongue to a slightly higher position, such adjustment may create a wrinkle in the cigarette paper which necessitates adjustment of the pastier section block. Moreover, there is a limit to the extent which the tongue may be adjusted without varying the size of the cigarette rod. With prolonged use, the inner surface of the tongue becomes glossy due to the friction of the tobacco thereon and "chokes" occur more frequently. Since chokes necessitate the adjustment of the tongue and the stoppage of the machine, it will be evident that considerable cigarette production is thus lost.

One of the objects of the invention is to provide a cigarette machine tongue which has an inner surface suitably roughened or pitted to reduce the formation of chokes. I have discovered that the formation of chokes may be reduced if the tongue is roughened or pitted by sand-blasting or indenting the inner surface of the tongue. The term sand blasting, as used in the specification and claims of this application, is employed in a generic sense and includes blasting with any small hard objects such as sand, shot and the like. I have produced indentations on the inner surface of the tongue by blasting the same with shot, and several shot-blasted tongues have operated satisfactorily in the commercial production of cigarettes on cigarette machines. However the indentations in the inner face of the tongue may also be produced by etching, engraving, stamping or rolling; and the indentations may be arranged to simulate knurling if desired.

If desired, only a minor section of the length of the tongue adjacent the smaller end from which the tobacco layer emerges may be pitted or roughened, so that the formation of chokes will be minimized. It should be noted that the

2

channel formed in the tongue has a breadth which diminishes gradually along its length toward its smaller end where the tobacco is compressed into a circular cross-section for a round cigarette or an oval cross-section for an oval cigarette rod, as the case may be. Accordingly, most of the compression of the tobacco occurs adjacent the smaller end of the tongue. Therefore it is another object of the invention to provide a cigarette machine tongue which was roughened or pitted only at a portion thereof adjacent its smaller end.

Since the tobacco is compressed by the tongue it is necessary to hold the edges of the cigarette paper against the longitudinal edges of the tongue to prevent the tobacco from escaping. For this purpose the block in which the paper is guided under the tongue has a tapering channel wherein the edges of the cigarette paper are gradually folded upwardly against the longitudinal edges of the tongue. If the inner surface of the tongue were roughened or pitted over its entire inner surface, the engagement of the paper with the indentations along the longitudinal edges of the tongue would cause the paper to be torn. Accordingly, still another object of the invention is to so roughen or pit the inner face of the tongue that the portions thereof adjacent its longitudinal edges are smooth. For this purpose the tongue may be blanked out in the form of a flat strip and its inner face may be suitably pitted along its length by sand-blasting, etching, engraving, stamping or rolling, except at the portions thereof adjacent its longitudinal edges. The blank is then folded into the customary shape wherein it has a channel of decreasing breadth. Thus a tongue will be formed having an inner surface which is pitted except along its longitudinal edges.

With these and other objects not specifically mentioned in view, the invention consists in certain constructions and combinations hereinafter fully described.

In the accompanying drawings which form a part of this specification and in which like characters of reference indicate the same or like parts:

Fig. 1 is a side elevation of a cigarette machine tongue embodying the invention;

Fig. 2 is a bottom view of the tongue shown in Fig. 1, showing indentations on the inner face thereof which simulate knurling, the vertical rib being omitted in this view;

Fig. 3 is a similar view of a tongue in which the vertical rib is omitted and the knurling is

provided on the inner surface of the tongue along a minor section of its length adjacent its smaller end;

Fig. 4 is a bottom view of a tongue whose inner surface has been roughened by sand-blasting, the vertical rib being omitted in this view;

Fig. 5 is a plan view of a flat blank from which the tongue is formed, the inner face of the blank being pitted by knurling except along the longitudinal edges;

Fig. 6 is an end view from its larger end of the tongue shown in Fig. 1;

Fig. 7 is a partial plan view of the rod former of a cigarette machine equipped with the improved tongue;

Fig. 8 is a front elevation thereof;

Fig. 9 is an end elevation thereof; and

Fig. 10 is a bottom view of the tongue shown in Fig. 1, showing indentations on the inner face thereof which have been made by molten metal projected on the surface thereof or by carborundum particles secured thereon.

As shown in Fig. 1, the cigarette machine tongue 10 has a tapering channel wherein the tobacco is compressed while being advanced on the cigarette paper into the rod former. The tongue 10 may be provided with a rib 17 which is secured to its top by soldering, brazing or welding. The rib 17 is provided with lugs 18 which are supported on a mount hereinafter described, to maintain the tongue in a predetermined relationship to a folder bottom provided with a tapered channel wherein the cigarette paper advances the continuous layer of shredded tobacco. The inner surface of the tongue may be provided with suitably pitted indentations 12, as illustrated in Figs. 2 and 6, which simulate knurling. Figures 2 and 6 of the drawings illustrate knurling of the type wherein indentations are visible to the eye as substantially fine lines representing almost imperceptible depth. The purpose of this showing is to convey an impression of an indentation less in depth than the average width of a cigarette shred. While the indentations 12 resemble diamond knurling, it may be stated that they may be arranged in the form of straight knurling or otherwise.

In Fig. 3 the tongue 20, which also has a tapering channel wherein the tobacco is compressed while advanced on the cigarette paper, is shown pitted with intersecting indentations 22 on the inner surface thereof adjacent the smaller end of tongue 20 from which the tobacco emerges after being compressed to a predetermined cross-section. Indentations 22 may simulate diamond knurling and preferably cover only a minor section of the length of the tongue, and may extend from the smaller end of the tongue to a point short of the middle of the tongue. Otherwise the tongue shown in Fig. 3 is identical with that shown in Figs. 1, 2 and 6.

In the case of the tongue 30 shown in Fig. 4, its inner surface is pitted by sand-blasting as indicated by the legend. The pitting provided thereon by sand-blasting serves to reduce the frequency of chokes. It is readily apparent that when sand-blasting, indentations will be formed which will intersect. This will also occur when the indentations in tongues are formed by shot blasting. A number of tongues of this type, wherein the inner surface has been sand-blasted to roughen the same, have been installed on cigarette machines and have been found to operate satisfactorily in commercial production.

In Fig. 5 there is shown a flat sheet metal blank

40 from which the cigarette machine tongue is formed. Blank 40 may be suitably pitted or roughened by indentations 42 extending along its entire length except at the portions thereof adjacent its longitudinal edges. These indentations 42 may be produced by etching, engraving, stamping or rolling, or they may be produced by sand-blasting. While the indentations 42 are illustrated as arranged to simulate diamond knurling, it will be understood that they may be arranged differently. Thus when blank 40 is bent into the channel shape shown in Figs. 1-4, a rib may be secured thereon and the tongue installed on a cigarette machine.

15 As an alternative the blank 40 may be sand-blasted or otherwise roughened after being bent into channel form. Moreover roughening of the inner surface of the tongue may be produced by molten metal projected thereon to form an uneven layer of solidified metal which is sufficiently rough to reduce "choking," or carborundum particles may be secured thereon in a suitable manner such as shown by the tongue 50 in Fig. 10.

The tongue 10 shown in Figs. 1, 2 and 6 is intended to coact with the portion of the rod former shown in Figs. 7-9. The structure shown in Figs. 7-9 is similar to that shown in the patent to E. D. Smith, No. 2,235,853, issued March 25, 1941, and includes a bottom insert 111 which is adjustable longitudinally in ways formed in a folder bottom or base member 112, constituting part of the supporting structure for the tongue.

This insert is held in place by screws 31 transfixing the walls of the bottom plate 112, and the tongue 10 is disposed between guide plates 113 which are secured by screws 114 to the folder bottom 112, the inner upright walls of the plates 113 preferably converging in the direction of travel of the rod forming tape 16 and paper web 15, and in conformity with the taper of the tongue 10.

45 The tongue 10 and the folder bottom insert 111 are slightly narrower at their receiving ends than the width of the cigarette paper 15, as shown in Fig. 7, and gradually taper off to about the diameter of the finished cigarette rod at the delivery end, the paper being carried, with the tobacco T distributed thereon, by the folder tape 16 through the rod-forming mechanism parts 10, 50 111 and 113, above mentioned, to and through the usual associated folder, paster and sealer mechanism, in known or suitable manner.

55 Rib 17 of the tongue 10 is formed with three lugs, as at 18, two of which preferably project from the same side of the tongue, being spaced apart by nearly the entire length of the rib 17, while the third lug 18 extends medially from the other side of the tongue, as shown in Fig. 7. In each of the lugs 18 is carried a vertical set-screw 60 19 adapted to engage a stop surface 120 on one of the two side blocks 121, each of these two blocks being preferably co-extensive in length with one of the underlying guide blocks 113, and being secured thereupon by the cap screws 114 65 which transfix the blocks 113 and 121 and are set into the bottom block 112. Two set-screws 122 with lock nuts 122a, and a thumb screw 123, all three of these screws transfixing the blocks 121, bear against the lugs 18 and determine the angular position of the tongue 10.

70 The lock nuts 190 and 122a serve to fix the tongue 10 in its desired position of adjustment. The tongue is maintained in its set position against the three point bearing determined by the contact of set screws 19 with the faces 120 of

the blocks 121 by releasable means comprising the screw 124 which is supported in an arm 125 adapted to be swung at will around a pivot post 126 on the block 121. This thumb screw 124, when brought down on top of the rib 17, secures the tongue in its operative position.

In the event that it becomes desirable to remove the tongue 10 for examination and repair, replacement or adjustment, the thumb screw 124 is backed-off, and the arm 125 is swung around, so that the tongue can be lifted clear after the thumb screw 123 has been backed-off. As the setting of screws 19 and 122 has not been disturbed, the tongue 10 can be returned to its identical original position when the above described operation shall have been preformed.

For the sake of convenience in locating the position where the thumb screw 124 is over the middle of the longitudinal rib 17, a pin 127 is preferably placed in the front locating block 121, and acts as a stop when the lug 28 on the arm 125 brings up against it, as illustrated in Fig. 1.

In order to prevent the tongue 10 from being displaced longitudinally from its set position, wings 29 may be provided on one of the lugs 18, as shown in Figs. 7 and 8, so arranged as to fit diametrically across the slot 30a in the front locating block 121.

To the tongues 20 and 30 shown in Figs. 3 and 4, there may also be secured a rib similar to rib 17 and provided with lugs similar to lugs 18, after which they may be mounted on the type of rod former shown in Figs. 7-9.

The invention above described may be varied in construction within the scope of the claims, for the particular device selected to illustrate the invention is but one of many possible embodiments of the same. The invention, therefore, is not to be restricted to the precise details of the structure shown and described.

What is claimed is:

1. A cigarette machine tongue comprising an elongated channel shaped member having a curved cross section and adapted to compress to a predetermined cross-section a layer of tobacco advanced on a traveling cigarette paper web, the concave tobacco engaging face of said member being pitted, said pits having a depth less than the average width of cigarette tobacco shreds operated on by said tongue and having unintersected lengths less than the width of the tongue.

2. A cigarette machine tongue comprising an elongated channel shaped member adapted to compress to a predetermined cross-section a layer of tobacco advanced on a traveling cigarette paper web, the tobacco engaging face of said member being irregularly pitted, similar to that obtained by sand-blasting.

3. A cigarette machine tongue comprising an elongated channel shaped member having a curved cross section and adapted to compress to a predetermined cross-section a layer of tobacco advanced on a traveling cigarette paper web, the concave tobacco engaging face of said member being pitted, with indentations extending across said face, said indentations having a depth less than the average width of cigarette tobacco shreds operated on by said tongue.

4. A cigarette machine tongue comprising an elongated channel shaped member having a curved cross section and adapted to compress to a predetermined cross-section a layer of tobacco advanced on a traveling cigarette paper web, the concave tobacco engaging face of said member being pitted along its entire length except at the

portions thereof adjacent the longitudinal edges thereof, said pits having a depth less than the average width of cigarette tobacco shreds operated on by said tongue, and having unintersected lengths less than the width of the tongue.

5. A cigarette machine tongue comprising an elongated channel shaped member having a curved cross section adapted to compress a layer of tobacco advanced on a traveling cigarette paper web to a predetermined cross-section, the concave tobacco engaging face of said member being pitted by indentations extending over only a portion of said face, said indentations having a depth less than the average width of cigarette tobacco shreds operated on by said tongue and having unintersected lengths less than the width of the tongue.

6. A cigarette machine tongue comprising an elongated tapered channel shaped member having a curved cross section and adapted to compress to a predetermined cross-section a layer of tobacco advanced on a traveling cigarette paper web, the concave tobacco engaging face of said member being provided with intersecting indentations.

7. A cigarette machine tongue comprising an elongated tapered channel shaped member having a curved cross section and adapted to compress to a predetermined cross-section a layer of tobacco advanced on a traveling cigarette paper web, the concave tobacco engaging face of said member being provided with intersecting indentations, said indentations simulating diamond knurling.

8. A cigarette machine tongue comprising an elongated tapered channel shaped member having a curved cross section and adapted to compress to a predetermined cross-section a layer of tobacco advanced on a traveling cigarette paper web, the concave tobacco engaging face of said member being provided with intersecting indentations, said indentations being formed only on a minor portion of the length of said face adjacent the exit end of said member.

9. In a cigarette machine, the combination with a tongue having an elongated member provided with a tapering channel curved in cross section and adapted to compress to a predetermined cross-section a layer of tobacco advanced on a traveling cigarette paper web, of a support for said paper web having a tapering channel wherein the paper web is guided underneath said tongue, the channel in said support being constructed and arranged to maintain the edges of the paper web in engagement with the longitudinal edges of said member, and the concave inner surface of the channel in said member being provided with individual transversely extending indentations, each having a depth less than the average width of cigarette tobacco shreds operated on by said channel in said member except at the portions of said concave surface adjacent the longitudinal edges of said member to avoid tearing of the paper web while it is held against said longitudinal edges.

10. In a cigarette machine, the combination with a tongue having an elongated member provided with a tapering channel of curved cross section and adapted to compress to a predetermined cross-section a layer of tobacco advanced on a traveling cigarette paper web, of a support for said paper web having a tapering channel wherein the paper web is guided underneath said concave channel, the channel in said support being constructed and arranged to maintain the edges of the paper web in engagement with the

longitudinal edges of said member, the inner surface of the channel in said member being scarred with scars of a depth less than the average width of a cigarette tobacco shred operated on by said channel and having unintersected lengths less than the width of the channel along its entire length to minimize the formation of "chokes" in the tobacco advanced through said channel except at the portions thereof adjacent the longitudinal edges of said member to avoid tearing of the paper web while it is held against said longitudinal edges.

11. A process for manufacturing a cigarette machine tongue comprising forming a tapered sheet metal blank, pitting one surface of said blank with pits of a depth that are less than the average width of cigarette tobacco shreds to be operated on by said blank, said pits extending across the width of said blank except along its longitudinal edges, and folding said pitted blank transversely to form a cigarette machine tongue having a longitudinal channel with the pitted surface on the inner face of said tongue.

12. In a cigarette rod former wherein a continuously traveling cigarette paper web is folded upwardly about a layer of tobacco carried by the paper web to form a cylindrical cigarette rod, the combination with a member having a concave face conforming to the curvature of the cigarette rod positioned above and coacting with said paper web to produce a cylindrical cigarette rod, said face extending longitudinally of the direction of travel of the paper web and being pitted with indentations of a depth less than the average width of cigarette tobacco shreds operated on by said member and having unintersected lengths less than the width of the member to prevent interruption of the movement of said tobacco layer during the formation of a cigarette rod in the rod former, of means for supporting said member in operative relation to the traveling cigarette paper web.

13. In a cigarette machine, the combination with an elongated tongue provided with a tapering channel having a curved cross section and adapted to compress to a predetermined cross-section a layer of tobacco advanced on a traveling cigarette paper web, of a support for said paper web underlying said tongue, said support having a tapering channel wherein the paper web is guided underneath said tongue and the

edges of the web are folded upwardly against the tongue while the layer of tobacco is compressed by the concave tongue, the inner face of said tongue being pitted to minimize "choking" of the layer of tobacco in the tongue, said pits having a depth less than the average width of cigarette tobacco shreds operated on by said tongue and having unintersected lengths less than the width of the tongue.

14. A process for manufacturing a cigarette machine tongue comprising forming a pitted surface on one face of a tapered sheet metal blank with pits of a depth less than the average width of cigarette tobacco shreds operated on by said tongue and having unintersected lengths less than the width of the tongue and folding the blank transversely to form a cigarette machine tongue having a longitudinal channel with the pitted surface on the inner face of said tongue.

15. In a cigarette machine, the combination with a tongue having a tapering elongated channel having a curved cross section and adapted to compress to a predetermined cross - section a layer of tobacco advanced on a traveling cigarette paper web, of a support for said paper web having a tapering channel wherein the paper web is guided under said tongue, the concave tobacco engaging face of said tongue being pitted only at the portion thereof adjacent the end of said tongue from which said tobacco layer emerges, said pits having a depth less than the average width of cigarette tobacco shreds operated on by said tongue and having unintersected lengths less than the width of the tongue.
